UNITED STATES PATENT OFFICE.

HIRAM S. THOMASSON, OF PORTLAND, IOWA.

SPARK-PLUG.

1,107,634.

Specification of Letters Patent. Patented Aug. 18, 1914.

Application filed October 2, 1912. Serial No. 723,599.

To all whom it may concern:

Be it known that I, HIRAM S. THOMASSON, a citizen of the United States, residing at Portland, in the county of Cerro Gordo and State of Iowa, have invented certain new and useful Improvements in Spark-Plugs; and I do hereby declare the following to be a full, clear, and exact description of the invention, such as will enable others skilled in the art to which it appertains to make and use the same.

This invention relates to spark plugs for igniting the charges of internal combustion engines by means of electricity; and it consists in the novel construction and combination of the parts hereinafter fully described and claimed.

In the drawings, Figure 1 is a side view of a spark plug constructed according to this invention. Fig. 2 is an end view of the spark plug. Fig. 3 is a longitudinal section through the spark plug.

The body portion 2 of the spark plug is provided with a chamber 3 at its inner end, 25 and a screwthreaded portion 4 which is screwed into a hole in the engine cylinder or combustion chamber in the usual way. The outer portion of the plug has a chamber 5 which is a little larger in diameter than the 30 chamber 3. A core 6 of insulating material is provided, and has a collar or enlargement 7 at its middle part which is secured in the chamber 5 by means of a screwthreaded gland 8, or other suitable fastening device. 35 The front end portion 9 of the core is smaller in diameter and shorter than the chamber 3, into which it projects, and it has a recess 10 in its inner end, and a hole 11 which extends longitudinally through its center. 40 The inner end of the plug is arcuate and is provided with a series of radial slots 14 which form a series of arcuate projections 15. A screwthreaded rod 16 is slidable longitudinally in the hole 11, and is provided 45 with an adjusting nut 17 which is arranged in the recess 10.

A perforated disk 18 is secured to the inner end of the rod 16 and overlaps the pro-

jections 15. As many perforations 24 as desired may be formed in the disk 18, and the 50 nut 17 is arranged so that the disk is held at a suitable distance from the rounded projections to form a series of spark gaps. The outer end of the rod 16 is provided with a fastening nut 19, and has a nut 21 for connecting the rod to a battery wire 20. Each time current is sent through the disk and plug, sparks are formed between the projections and the disk, and the inflammable charge in the engine cylinder is ignited. 60 The charge in the chamber 3 is also ignited and it blows out therefrom all accumulations of oil, carbon or other material which would otherwise block the narrow spaces between the disks and the projections. Several of 65 these spaces may become obstructed without wholly preventing the formation of sparks, and the size and number of the vent slots 14 and the perforations 24 regulate the cleaning action at the spark gaps, and prevent it 70 from being too violent. The central location of the rod 16 prevents the parts from getting out of adjustment.

What I claim is:

In a spark plug, the combination, with a 75 plug body having a gas chamber in its inner end portion, and a series of slots in its inner end which form electrode projections, of a core of insulating material secured in the plug body with its outer end portion projecting therefrom, said core having a central hole and having a recess in its inner end portion, a screwthreaded rod which projects through the said core and gas chamber, adjusting nuts screwed on the said rod and securing it in the core, one of the nuts being arranged in the said recess, and a perforated electrode disk secured on the inner end of the said rod and overlapping the said electrode projections and the gas chamber. 85 90

In testimony whereof I have affixed my signature in the presence of two witnesses.

HIRAM S. THOMASSON.
